UNITED STATES PATENT OFFICE.

JOHN S. BOHEN, OF SPRINGFIELD, VERMONT, ASSIGNOR OF ONE-HALF TO JOHN J. COSTELLO, OF PITTSFIELD, MASSACHUSETTS.

MULTIPLE SWITCH.

Application filed March 22, 1927. Serial No. 177,450.

My invention relates to a multiple switch having contacts for several circuits, and it has particular reference to that class of such devices that are used for illumination and 5 ignition.

One of the objects of the device is to provide a multiple switch that is encased in a housing in which the electrical contacts are concealed, and the device operated by means 10 of a knob that works in a longitudinal slot.

Another object of the invention is to provide a multiple switch in which one or more circuits may be used, and all circuits operated from a common knob without interference with or from the other circuits. 15

Figure 1 is a sectional plan view taken on the line 1—1 of Figure 2.

Figure 2 is an elevation view in part section:

20 Figure 3 is a sectional view of one of the blade terminals and terminal plate.

Figure 4 is a side view of the segment contact.

25 Figure 5 is a front view of the segment contact and segment terminal.

Similar numerals of reference indicate similar parts thruout the several views.

Referring to the drawings 7 indicates a terminal plate that is inserted in the casing 30 1. The casing 1 is provided with a support 2 secured thereto, and a semicircular support 3 is fastened to the casing support 2 by means of bolts that are inserted into the holes 16. The purpose of the casing support 35 2 and the semi-circular support 3 are to provide the means whereby the switch may be fastened in position, and the switch may be fastened in position by means of the casing support 2, alone, or the semicircular support 3 may be used in connection with the 40 casing support 2 to fasten the switch around an object by using the semicircular support 3 as a clamp.

The terminal plate 7 is provided with two 45 blade terminals 9, and a stud 4 extends from each terminal, and an insulating bushing 6 is placed over each terminal stud to prevent the current from leaking into the terminal plate 7. A segment terminal 10 is placed 50 centrally between the blade terminals 9 and a terminal stud 4 extends from the segment terminal, an insulating bushing 6 is also placed over the segment terminal 10 to prevent any leakage from the current into the 55 terminal plate 7. The terminal studs 4 are

provided with nuts 5 for making connections to an electrical circuit. The inside of the terminal plate 7 is provided with insulating material 8 to prevent any leakage of the 60 current into the terminal plate 7.

A segment contact 11 is pivotally connected to the segment terminal 10, and the segment contact 11 is provided with a projection 21. A pin 17 passes thru the projection 21 on the segment contact 11 and is held in position by means of the split washers 18, and the said pin is so designed that it may be rotated within the projection 21. A knob 12, which is composed of insulating material, is secured to the pin 17, and the device is operated by means of this knob. A contact blade 14 is rigidly secured to the pin 17 and rotates with the said pin. 70

One side of the casing 1 is provided with 75 a terminal stud 20 that passes thru the casing and thru an insulating bushing 6, and the stud is connected to the contact plate 13. The contact plate 13 consists of resilient material and is turned over on the ends as indicated by the numeral 22, to allow a greater resiliency in the center of the contact plate 13 when it is brought in contact with the contact blade 14 which is caused by operation of the knob 12. A casing insulation 23 is placed around the inside of the casing, and the contact plate 13 is held in contact with the casing insulation by means of the stud 20. A support 21' is secured to the contact plate 13 and extends to the bottom of the casing and is for the purpose of preventing the contact plate 13 from twisting or turning. The stud 20 is also provided with nuts 5 for making connection to an electrical circuit. 80 85 90 95

The operation of the device is as follows:

The casing is provided with a longitudinal slot 15 and the pin 17 projects thru this slot to the outside of the casing and is provided with a knob 12. When it is desired to make 100 connection and complete the circuit the operator moves the knob either to the right or left, as the case may be, along the slot 15 and this will cause the segment contact to turn on the pin 19 and make contact with the terminal blade 9 as shown by the dotted lines of the segment contact. While the segment contact is in contact with the terminal blade 9, and it is desired to make contact with another circuit, all that is necessary is to 110 turn the knob 12 and the contact blade 105

14 will be brought in contact with the contact plate 13. If desired to disconnect the segment contact from the terminal blade 9 this can be done by simply moving the knob 5 along the longitudinal slot 15 and the contact blade 14 will slide along the contact plate 13 and still retain the circuit between the contact plate 13 and the segment terminal 10. If it is desired to make connection to the opposite terminal blade 9, this can be done by moving the knob 12 farther along the slot 15 and the segment contact 11 will be brought in contact with the opposite terminal blade 9 and complete the 15 circuit.

Having thus described my invention what I claim as new, and desire to secure by Letters Patent, is:—

A multiple switch comprising a casing 20 provided with a longitudinal slot, a sup-

port for said casing, a terminal plate attached to the inner side of the casing, a plurality of terminals attached to the terminal plate with terminal studs extending therefrom, a contact segment pivotally attached to one of the said terminals, a contact plate of resilient material provided with a terminal stud extending therefrom, an operating knob, provided with a contact blade attached to a pin extending from 30 said knob, and said pin rotatably attached to a projection on the segment terminal and operated to make various circuit connections in cooperation with the various terminal connections by moving or turning 35 or moving and turning the said pin by means of the knob along or within the longitudinal slot in the casing.

In testimony whereof I affix my signature.
JOHN S. BOHEN.
